UNITED STATES PATENT OFFICE.

WILLIAM H. HACKMAN, OF CHAPMAN, KANSAS.

GRAIN SPROUTER.

Application filed March 31, 1924. Serial No. 703,278.

To all whom it may concern:

Be it known that I, WILLIAM H. HACKMAN, a citizen of the United States, residing at Chapman, in the county of Dickinson and State of Kansas, have invented certain new and useful Improvements in Grain Sprouters, of which the following is a complete specification.

My invention relates to improvements in grain sprouters and particularly to that type, in which the grain is subjected to a current of warm, moist air.

The object of my invention is to provide a grain sprouter, in which a current of warm, moist air is continually passing over the grain; another object is to provide a grain sprouter, by means of which grain may be quickly sprouted, without the necessity of stirring the grain or opening the sprouter door to allow proper ventilation to prevent souring or moulding of the grain.

A still further object of my invention is to so space the grain trays in the sprouter, as to admit sufficient light to all parts of the sprouter to produce the proper greening of the sprouts.

With the foregoing general objects in view, the invention will now be described by reference to the accompanying drawings illustrating one form of construction which I have devised for embodying the invention, after which the various novel features therein will be particularly set forth and claimed.

In the drawings:

Fig. 1 is a perspective view of my grain sprouter with the closure opened.

Fig. 2 is a vertical section of the same taken along line II—II of Fig. 1, looking in the direction of the arrow.

Fig. 3 is a vertical section taken on line III—III of Fig. 1 with the closure closed.

Fig. 4 is a horizontal section taken on line IV—IV of Fig. 2.

Fig. 5 is an enlarged fragmentary sectional view, similar to Fig. 3, showing the supporting brackets for the grain trays, in position; and,

Fig. 6 is a perspective view of the grain tray supporting bracket, detached from the cabinet.

Similar reference characters designate like parts throughout the several views, in which 1 designates a cabinet made of any suitable material and lined with roofing or any material that is impervious to moisture. In the illustration, this cabinet 1 has been

shown as a unit but may be made in the well known sectional form if desired.

Cabinet 1 is divided into an upper and lower compartment 2 and 3 respectively by means of a water pan 4 which is supported on a bracket 4A.

The rear side of the cabinet is provided with an opening 5 having a closure 6, the bottom edge of which is spaced apart from the bottom edge of the cabinet 1, thus forming an inlet 7, by means of which air is furnished to the heater 8.

For purposes of illustration, the heater 8 is shown to be an ordinary heating lamp, but any other suitable heating means may be used.

Side walls 1A and 1B of the cabinet 1 are provided with a plurality of air openings 9 which communicate with compartment 3 and serve as vents for the fumes from heater 8.

The front wall of the cabinet is provided with transparent or translucent panels 10, through which light passes to all parts of the upper compartment 2. Cabinet 1 is further provided at its top with an air outlet 12, while air inlets 11 are cut through its side wall 1A in such a way as to communicate with compartment 2 at a point adjacent the water pan 4.

Interposed between air inlets 11 and air outlet 12, of compartment 2, are a plurality of grain trays 13 having perforated bottoms 14, through which the excess moisture may be discharged. Grain trays 13 are supported in a horizontal position within the cabinet by means of fixed brackets 15, and extend alternately from opposite walls of cabinet 1 to within a distance of the other wall thereof, to form a zigzag passage between said air inlets 11 and air outlet 12. The lowest grain tray 13 extends from wall 1A and just above the air inlets 11 to within a distance of the opposite wall 1B, thus making it necessary for the air which enters inlets 11 to pass over the surface of the water in pan 4.

The bracket 15 which is best illustrated in Fig. 6, is so constructed as to admit of an easy insertion of the grain trays.

Operation.

In the operation of my improved grain sprouter, the grain is placed in grain trays 13, in thin layers, the trays 13 are then inserted through opening 5 into compartment

2 where they are supported on brackets 15. Water is placed in water pan 4 and the heater 8 lighted, after which closure 6 is closed.

5 Through the influence of the heater 8, the water in pan 4 becomes heated, in turn heats and moistens the adjacent air which starts a circulation of the same around the end of the lowest grain tray 13, thence across its
10 upper surface, around the opposite end of the next grain tray above, and so on to the air outlet 12 at the top of cabinet 1. This upward current of air causes a flow of air to pass in through the air inlets 11 which
15 must pass over the surface of the heated water in water pan 4 and become saturated. The grain being subjected to this warm moist air, sprouts rapidly. All excess moisture that may collect in the grain trays,
20 drains through the perforated bottoms 14 of trays 13 and then back into the water pan 4.

The zigzag passage for the air, which is best illustrated by arrows in Fig. 2, causes
25 the warm moist air to pass over all the grain, thus preventing any dead air spaces where the grain might sour or mould.

The grain trays 13 are so spaced apart, to permit the light, which enters through
30 transparent panels 10, to sufficiently illuminate all parts of the compartment 2 and cause a proper greening of all the sprouts.

It will thus be seen that I have devised a comparatively simple, compact and efficient arrangement and construction for fulfilling the desired object of the invention, and while I have illustrated what now seems to constitute the preferred form of construction, I desire to reserve the right to make
35 such changes or modifications as may fairly fall within the scope of the following claims.

What I claim is:

1. In a grain sprouter, in combination, a
40 cabinet having an air inlet and an air outlet, a plurality of grain trays interposed between said air inlet and air outlet and extending alternately from opposite walls of the cabinet to form a continuous air passage, of substantially uniform cross-section, from said air outlet, a water pan located beneath said air inlet, heating means for

said water pan and a transparent panel in said cabinet wall.

2. A grain sprouter provided with a cabinet, having an air inlet, an air outlet, a plurality of grain trays interposed between said air inlet and said air outlet and extending alternately from opposite sides of said cabinet to within a distance
55 from the other wall thereof, to form a zigzag passage from said air inlet to said air outlet, a water pan below said air inlet and means for heating said water pan.

3. A grain sprouter provided with a cabinet, having an air inlet, an air outlet, a plurality of perforated grain trays interposed between said air inlet and said air outlet, arranged one above the other and extending alternately from opposite sides of the cabinet to form a zigzag passage from said air inlet to said air outlet, a water pan located beneath said air inlet, heating means for said water pan and a transparent section in
60 said cabinet wall.

4. A grain sprouter provided with a cabinet, having an air inlet, an air outlet, a plurality of grain trays interposed between said air inlet and said air outlet and extending alternately from opposite sides of the cabinet to form a zigzag passage from said air inlet to said air outlet over the surface of each of said grain trays, a water pan supported beneath said air inlet, a heater for
65 said water pan, and a transparent panel in said cabinet wall.

5. A grain sprouter provided with a cabinet, having a lower and an upper compartment, the said lower compartment being provided with heating means, said upper compartment having a water container at its lower portion, an air inlet in its side wall adjacent said water container, an air outlet at its top, a plurality of grain trays interposed between said air inlet and said
70 air outlet and extending alternately from opposite sides of said cabinet to form a zigzag passage from said air inlet to said air outlet and a transparent panel in its front wall.

In testimony whereof I hereunto affix my signature.

WILLIAM H. HACKMAN.
